UNITED STATES PATENT OFFICE.

WILLIAM J. WISWALL, OF OAKLAND, CALIFORNIA, ASSIGNOR TO AMERICAN SALES BOOK COMPANY, LIMITED, OF TORONTO, ONTARIO, CANADA, A CORPORATION OF ONTARIO.

MANIFOLD-FORM-REGISTERING DEVICE FOR BILLING MACHINES.

Application filed March 17, 1924. Serial No. 699,864.

To all whom it may concern:

Be it known that I, WILLIAM J. WISWALL, a citizen of the United States, residing at Oakland, in the county of Alameda and State of California, have invented certain new and useful Improvements in Manifold-Form-Registering Devices for Billing Machines, of which the following is a full, clear, and exact description, such as will enable others skilled in the art to which it appertains to make and use the same.

This invention relates to an improvement for billing machines, and more particularly to form registering devices therefor.

An object of this invention is to functionally and structurally improve the operating mechanism of a billing machine, whereby greater convenience and accuracy of operation is attained.

A further object is to provide an improved mechanism for maintaining the registry of the forms on the superposed strips during the typing and feeding of the forms.

A further object is to provide a new and improved means for retaining the strips in registry during the reversed movement of the carbon carrier.

Other objects of the invention will in part be obvious and will in part appear hereinafter.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention reference should be had to the following detailed description taken in connection with the accompanying drawing, in which:

Figure 1 is a side elevation in part of the improved machine,

Fig. 2 is a plan view of a portion of the carriage extension, and the carbon carrier,

Figs. 3 and 4 are sections on the lines 2—2 and 4—4 of Fig. 2,

Fig. 5 is a perspective view of one end of the pin guard,

Fig. 6 is a similar view of the pin supporting plate and counterweight,

Fig. 7 is a perspective view of the manu-

ally controlled strip holding means and its support,

Fig. 8 is a sectional elevation on line 8—8 of Fig. 2,

Fig. 9 is a plan view of a part of one of the strips.

In the present embodiment of the invention the frame of a billing machine is shown at 1, which frame supports a carriage 2 having a platen roll 3 rotatable about a shaft eccentric to it and restrained from rotation by a platen roll release lever 4. Guide or truck rails 5 extend rearwardly of the carriage intermediate the sides thereof and upon the guide rails is mounted a carbon sheet carrier 6. This carrier is provided with a means indicated at 7 for supporting the carbon blades, which in turn support the carbon or transfer sheets, which are arranged between the strips of connected forms, the superposed strips being indicated at 8. The carrier is movable longitudinally of the trackrails 5, and it is moved forwardly by the tension on the strips caused by the turning of the platen roll as the forms are typed. The carrier is moved rearwardly, that is away from the carriage, by means of an arm 9 which extends forwardly from the carrier, to a position near the platen roll release lever 4. As the forms on the strips are filled in, the platen roll is turned, in the usual manner, and the carbon or transfer sheet carrier 6 is automatically moved forward, so that the carbon or transfer sheets are held in the proper position between the superposed strips, during the filling out of the forms.

The mechanism for maintaining the registry between the sheets is supported by the carbon carrier 6. The said mechanism includes a base plate 10 in rear and above the carriage and carried thereby. The superposed strips 8 pass over this base plate, 95 and are then interleaved with the transfer sheets and pass thence to and around the platen roll.

The strips are preferably similar, each carrying printed forms thereon and each strip having apertures 11 bearing definite relation to the printed forms. The web may moreover be provided with weakened lines 12 to separate the individual forms to facilitate the detachment of the forms from each other. The registry maintaining mechanism

- cooperating with the apertures includes a pair of pins 13 which are movable through openings in the base plate. The pins 13 and the openings are spaced to correspond with the spacing of the apertures 11, when the strips are properly placed on the machine, and the pins are normally moved into operative, that is into engaging position, by mechanism to be described. The pins are supported by a bar 15, which has a lost motion connection with one end of a lever 16 pivoted at 17 to the base 10. This lever arches downwardly, and at its free end, that is at the end remote from the plate or bar 15, the lever has a counterweight 18, which normally presses the bar toward the base plate, and normally extends the pins through the openings of the base plate. The bar 15 is guided in its movement toward and from the base plate by guide pins 19 depending from the base plate, and engaging openings in the bar. The lever 16 is at the center of the bar, and normally it holds the pins in position to engage the apertures of the superposed strips.
- The base plate 10 is provided at each end with an upwardly extending flange 20, and the strips move between the flanges. A clamping or guide bar 21 is mounted above the base plate, at the pins, the said bar being hinged to the base plate at one end as indicated at 22, and having a detachable connection 23 with the base plate at the other end. The connection is a spring latch as shown. The bar has on its under side an opening 24 for each pin, in which the rounded end of the pin is received, when the bar is in closed position, and when the pins are extended above the base plate.
- The superposed strips 8 pass between the base plate and the clamping bar, and it will be evident that when the corresponding apertures of the superposed strips are in register with each other, and with the pins, the counterweight will extend the pins through the apertures and into engagement with the openings of the clamping bar, to thus maintain registry between the strips during the filling in of the forms thereon.
- In order to release the strips, after a set of forms has been filled in by the machine, a trip is provided, for engagement by the free end of the lever 16, to lift the counterweight, thereby to lower the pins below the base plate, to release them from the apertures of the forms. The trip is adjustable longitudinally on the track rails 5 and comprises a pair of similar clamping bars, which are connected by a plate 25. The plate is provided at each end with a pair of spaced bearings 26, and the clamping bars are journaled in the bearings. Each bar comprises a tubular body 27, having at each end a clamp or foot 28 and 29. One of the feet 28 is rotatably connected with the body, while the other 29 has a threaded connection with the body, the arrangement being such that when the body is turned with respect to the foot 29, the said foot will be moved toward or from the foot 28, depending upon the direction in which the body is turned. By means of the clamp bars the trip may be adjusted to any desired position, so that the lever 16 will be operated to release the pins from the strips at any desired point in the travel of the carrier. When the pins have been released from the strips, the carrier is returned to its rearward position by means of the arm 9, and a suitable stop indicated at 30 is provided for limiting the rearward movement of the carrier, the stop being adjustably connected with the carriage. The superposed strips 8 are passed from the pad, which is arranged in rear of the machine, as shown in Fig. 1, over a guide roll 31 to the transfer sheet carrier. Mechanism is provided to hold the strips in registry during the return movement of the transfer sheet to carrier while the pins are out of engagement with the apertures of the strips. The said mechanism includes a gauge plate 32 which is secured to the carriage in any suitable manner, at the center of the platen roll. A head 33 is adjustably mounted on the gauge plate, and the head carries a pair of upstanding pins 34, which are spaced apart a distance corresponding to the spacing of the apertures 11 of the strips. Intermediate its ends the head is provided with a depending stirrup 35, and the stirrup walls have registering openings through which the gauge plate passes. A set screw 36 is threaded through the body of the stirrup, and engages the gauge plate, to hold the head in adjusted position. By loosening the screw, the head may be adjusted longitudinally of the gauge plate.
- In operation, to load the machine, the strips are drawn forwardly over the base plate 10 and beneath the platen roll. By means of the gauge plate 32 the platen roll and connected parts are swung forwardly and the strips are passed beneath the platen roll and pulled forwardly until the endmost apertures 11 will engage the pins 34 of the head. The platen roll is now returned to the position shown in Fig. 1 after which the carrier 6 is moved rearwardly until it engages the stop 30, it being understood that the strips have been interleaved with the transfer sheets before the said strips are engaged with the pins 34. As the carrier moves rearwardly, the upper rounded ends of the pins 13 engage the under face of the lowermost strip, and this engagement continues until the carrier engages the stop, at which moment the pins will engage within the apertures 11 of the strips. As the strips move forwardly under the pull of the platen roll, the carrier travels with them, and the

strips are maintained in exact registry. When a form has been filled in, the strips have been advanced far enough to engage the pins 34 of the head with the succeeding pair of apertures 11, and when they are so engaged, the engagement being brought about manually, the carrier is moved rearwardly. At the end of the forward movement of the carrier, the engagement of the counter-weight 18 with the stop or trip 25 releases the pins from the apertures with which they are engaged, and the slight further movement of the strips in order that a succeeding set of apertures may be engaged 15 with the pins 34 moves the apertures out of register with the pins 13, so that the return movement of the carrier is not interfered with. In first loading the machine the strips are placed in succession from the lowermost 20 to the uppermost, to facilitate their inter-leaving with the transfer sheets. After a set of filled in forms has been released from the pins 34, the set may be torn off by engaging them with a cutting blade, not shown, 25 adjacent to the platen roll. The provision of the counter-weight for extending the pins 13 insures the proper operation of the pins without the use of springs or the like, and there is no possibility of sticking or catching 30 of the pins. The first forward movement of the platen roll in typing a new set of forms loosens a preceding set from the pin 34.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters 50 Patent, is:

1. In a machine of the class described, the combination with a carriage and a carbon carrier, supported thereon of pins on the carrier for engaging aligning apertures in the paper strips, a counterweight to extend the pins, a stop on the carriage for engagement by the counterweight to release the pins, manually controlled means for holding the strips from rearward movement with the carrier, including a bar carrying aligning pins, a gauge plate on the carriage on which the bar is slid able, and means for holding the bar in adjusted position.

2. In a machine of the class described, the combination with a carriage and a carbon

carrier supported thereon, of pins on the carrier for engaging aligning apertures in the paper strips, a counterweight to extend the pins, a stop on the carriage for engagement by the counterweight to release the pins, manually controlled means for holding the strips from rearward movement with the carrier, including a bar carrying aligning pins, a gauge plate on the carriage on which the bar is slid able, the bar having a stirrup 70 75 80 85 90 95 100 105 110 115 120 125 130 135 140 145 150 155 160 165 170 175 180 185 190 195 200 205 210 215 220 225 230 235 240 245 250 255 260 265 270 275 280

means for holding the stirrup into engagement with the gauge plate.

3. In a machine of the class described, the combination with a carriage having means to support and advance superposed paper strips provided with aligning openings, of a carrier on the carriage mounted to move with and to be moved by the strips, pins on the carrier for engaging the aligning apertures; a counterweight to extend the pins, a stop on the carriage for engagement by the counterweight to release the pins, manually controlled means for holding the strips from rearward movement with the carrier, including a bar carrying aligning pins, a gauge plate on the carriage on which the bar is slid able, means for holding the bar in adjusted position, said bar having a stirrup 95 100 105 110 115 120 125 130 135 140 145 150 155 160 165 170 175 180 185 190 195 200 205 210 215 220 225 230 235 240 245 250 255 260 265 270 275 280

1. In a machine of the class described, in combination, a carriage, a carrier supported by said carriage and having counterweighted aligning pins for engaging apertures in a set of record strips to hold them in registry as they are drawn toward the platen roll, a stop on the carriage to engage and lift the counterweight to release the pins at the end 100 105 110 115 120 125 130 135 140 145 150 155 160 165 170 175 180 185 190 195 200 205 210 215 220 225 230 235 240 245 250 255 260 265 270 275 280

2. In a machine of the class described, in combination, means for supporting in position for entry of a record a set of superposed record sheets or strips each having similar blank forms positioned therealong and having a series of control apertures therein bearing a definite relation to said blank forms, a movable carrier engaging and traveling with said superposed sheets during feeding movement thereof, a movably mounted pin on said carrier for engagement in said apertures of a superposed set of sheets to maintain 130 135 140 145 150 155 160 165 170 175 180 185 190 195 200 205 210 215 220 225 230 235 240 245 250 255 260 265 270 275 280

said sheets in longitudinal alignment during feeding thereof, a counterweight connected to said pin to urge it into position for engagement with said apertures, means controlled by advancement of said carrier for automatically withdrawing said pin from the apertures in opposition to the action of the counterweight to release the strips and being operative automatically to restore the 10 pin to the influence of the counterweight upon reverse movement of said carrier thereby projecting the pin into frictional engagement with the sheet and projecting it into the next successive aperture with which it 15 comes into alignment in the reverse movement of said carrier.

6. In a machine of the class described, in combination, means for supporting in position for entry of a record a set of superposed 20 record sheets or strips each having similar blank forms positioned therealong and having a series of control apertures therein bearing a definite relation to said blank forms, a movable carrier engaging and traveling with said superposed sets during feeding movement thereof, a movably mounted pin on said carrier for engagement in said apertures of a superposed set of sheets to maintain said sheets in longitudinal alignment during feeding thereof, a counterweight connected to 25 said pin to urge it into position for engagement with said apertures, means controlled by advancement of said carrier for automatically withdrawing said pin from the apertures in opposition to the action of the 30 counterweight to release the strips and being operative automatically to restore the pin to the influence of the counterweight upon reverse movement of said carrier thereby projecting the pin into frictional engagement with the sheet and projecting it into the next successive aperture with which it 35 comes into alignment in the reverse movement of said carrier, and a gauge plate on the machine having a pin mounted thereon for engagement 40 with forwardly advanced apertures in the sheets when said first mentioned pin engages in less advanced apertures upon reverse carrier movement so as to effect stretching and longitudinal alignment of the 45 sheets.

7. In a machine of the class described, in combination, means for supporting in position for entry of a record, a set of superposed 50 record sheets or strips each having similar blank forms positioned therealong and having a plurality of series of control apertures therein bearing a definite relation to said blank forms, a movable carrier engaging and traveling with said superposed record sheets during feeding movement thereof, a movably mounted bar carrying a plurality of aligning pins for engagement in 55 said apertures of a superposed set of sheets to maintain the sheets in longitudinal alignment during feeding thereof, a lever operatively connected to said movably mounted bar, a counterweight connected to said lever to urge said pins into position for engagement with said apertures, a trip member engageable with said lever during advancement of said carrier for automatically withdrawing said pins from the control apertures in opposition to said counterweight to release the sheets and operating to automatically restore the pins to the influence of the counterweight upon reverse movement of said carrier thereby projecting the pins into frictional engagement with the sheets and projecting them into the next successive apertures with which they come into alignment in the reverse movement of said carrier.

8. In a machine of the class described, in combination, means for supporting in position for entry of a record, a set of superposed record sheets or strips each having similar blank forms positioned therealong and having a plurality of series of control apertures therein bearing a definite relation to said blank forms, a movable carrier engaging and traveling with said superposed record sheets during feeding movement thereof, a movably mounted bar carrying a plurality of aligning pins for engagement in said apertures of a superposed set of sheets to maintain the sheets in longitudinal alignment during feeding thereof, a lever operatively connected to said movably mounted bar, a counterweight connected to said lever to urge said pins into position for engagement with said apertures, a trip member engageable with said lever during advancement of said carrier for automatically withdrawing said pins from the control apertures in opposition to said counterweight to release the sheets and operating to automatically restore the pins to the influence of the counterweight upon reverse movement of said carrier thereby projecting the pins into frictional engagement with the sheets and projecting them into the next successive apertures with which they come into alignment in the reverse movement of said carrier.

9. In a machine of the class described, in combination, means for supporting in position for entry of a record, a set of superposed record sheets or strips each having similar blank forms positioned therealong and having a series of control apertures therein bearing a definite relation to said blank forms, a movable carrier engaging and traveling with said superposed record sheets during feeding movement thereof, a movably mounted bar carrying a plurality of aligning pins for engagement in said apertures of a superposed set of sheets to maintain the sheets in longitudinal alignment during feeding thereof, a lever operatively connected to said movably mounted bar, a counterweight connected to said lever to urge said pins into position for engagement with said apertures, a trip member engageable with said lever during advancement of said carrier for automatically withdrawing said pins from the control apertures in opposition to said counterweight to release the sheets and operating to automatically restore the pins to the influence of the counterweight upon reverse movement of said carrier thereby projecting the pins into frictional engagement with the sheets and projecting them into the next successive apertures with which they come into alignment in the reverse movement of said carrier, and a gauge plate on the machine having pins mounted thereon for engagement with forwardly advanced apertures in the sheets when said first mentioned pins engage in less advanced apertures upon reverse carrier movement so as to effect stretching and longitudinal alignment of the sheets.

10. In a machine of the class described, in combination, means for supporting in position for entry of a record, a set of superposed record sheets or strips each having similar blank forms positioned therealong and having a series of control apertures therein bearing a definite relation to said blank forms, a movable carrier engaging

- and traveling with said superposed sheets during feeding movement thereof, a movably mounted pin on said carrier for engagement in said apertures of a superposed set 5 of sheets to maintain said sheets in longitudinal alignment during feeding thereof, a counterweight connected to said pin to urge it into position for engagement with said apertures, means controlled by advancement 10 of said carrier for automatically withdrawing said pin from the apertures in opposition to the action of the counterweight to release the strips and being operative automatically to restore the pin to the influence 15 of the counterweight upon reverse movement of said carrier thereby projecting the pin into frictional engagement with the sheet and projecting it into the next successive aperture with which it comes into alignment 20 in the reverse movement of said carrier, and a guide bar on said carrier mounted for movement to and from sheet guiding position in which it cooperates with said pin.
10. In a machine of the class described, in combination, means for supporting in position for entry of a record, a set of superposed record sheets or strips each having similar blank forms positioned therealong and having a plurality of series of control 25 apertures therein bearing a definite relation to said blank forms, a movable carrier engaging and traveling with said superposed record sheets during feeding movement thereof, a movably mounted bar carrying a plurality of aligning pins for engagement in 30 said apertures of a superposed set of sheets to maintain the sheets in longitudinal alignment during feeding thereof, a lever opera-
- tively connected to said movably mounted bar, a counterweight connected to said lever 40 to urge said pins into position for engagement with said apertures, a trip member engageable with said lever during advancement of said carrier for automatically withdrawing said pins from the control apertures 45 in opposition to said counterweight to release the sheets and operating to automatically restore the pins to the influence of the counterweight upon reverse movement of said carrier thereby projecting the pins into 50 frictional engagement with the sheets and projecting them into the next successive apertures with which they come into alignment in the reverse movement of said carrier, and a guide bar on said carrier mounted 55 for movement to and from sheet guiding position in which it cooperates with said pins.
11. In a machine of the class described, in combination, a carrier having a supporting plate with apertures therein, a supporting bar movably mounted beneath said plate carrying pins adapted to project through said apertures so as to engage in corresponding apertures in one or more superposed record strips or sheets, an operating lever for 60 said pin supporting bar mounted on said carrier, a counterweight carried by said lever and being normally operative to project said pins into position to enter the apertures in the record strips and a tripping member positioned in the path of movement of said lever to automatically retract said pins.

In testimony whereof I affix my signature.
WILLIAM J. WISWALL.
